IMPACT WRENCH CONTROL

William S. Dale, Kingston, R.I., and Philip R. Haskell, Fairfield, Conn., assignors to Remington Arms Company, Inc., Bridgeport, Conn., a corporation of Delaware

Filed Feb. 26, 1959, Ser. No. 795,853

6 Claims. (Cl. 64-27)

This invention relates to power driven impact torque wrenches and the art of controlling the output of such impact wrenches.

More specifically this invention is concerned with the provision of an improved compact attachment device for use with conventional rotary impact wrenches or incorporated in new tools to selectively and accurately control and limit the maximum torque applied to a driven member.

Generally, most power impact wrenches on the market today have a maximum torque output which is above the maximum required or desirable in the tightening of some of the nuts or bolts they are intended to handle. While this extra power is useful in removing "frozen" or rusted fasteners, many times it results in tightening some fasteners to failure if the tool is applied too long. Slip clutches have been found inapplicable in the solution of this problem of limiting impact type torques applied to fasteners. No satisfactory device has appeared which offers a compact, wide torque range, accurate means of infinitely controlling or limiting the torque applied to a fastener device by a rotary impact wrench. In addition, presently known tools cannot be operated in a reverse direction without elaborate resetting and recalibration to the torque control unit.

It is an object of this invention to provide a novel effective device for selectively and accurately controlling the torque applied to fastener devices by a rotary impact tool over a wide range of torques.

It is another object of this invention to provide a device as discussed above which will function without adversely affecting the horsepower of the overall tool.

It is another object of this invention to provide such a device which is compact in size, light in weight, simple and reliable in construction.

It is yet another object of this invention to provide a tool which is continuously and infinitely adjustable to any torque within wide limits without any heavy or complicated tools, and which will function as aforesaid and be capable of immediate reversal of direction of operation without modification or adjustment.

Other objects and advantages will appear in the following description, the appended claims and the accompanying drawings in which:

Fig. 1 is a longitudinal cross-sectional view of one form of torque limiting device embodying features of the present invention.

Fig. 2 is an end view of the device of Fig. 1.

Fig. 3 is a view of the other end of the device of Fig. 1.

Fig. 4 is a side elevational view of the device of Fig. 1.

Fig. 5 is a transverse cross-sectional view taken on line 5-5 of Fig. 1.

Fig. 6 is a longitudinal cross-sectional view of a modified version of a torque limiting device embodying features of the present invention.

Fig. 7 is an end view of the device of Fig. 6.

Fig. 8 is a view of the other end of the device of Fig. 6.

2

Fig. 9 is a transverse cross-sectional view taken on line 9-9 of Fig. 6.

Fig. 10 is a side view of a torque limiting device as disclosed in this application showing its positional relationship to a conventional power impact wrench and the bolt or nut-engaging socket as used therewith.

Figs. 11-14 are corresponding views showing yet another modified version of a torque limiting device embodying features of the present invention.

10 The improved torque limiting device of this invention may be utilized as an attachment unit or built into pneumatic or electric power wrenches as an integral component thereof. The device may be utilized in connection with tools of the general type disclosed by the Pott U.S.

15 Patent No. 2,012,916, issued August 27, 1935, or of the general type disclosed by the Disser U.S. Patent No. 2,608,118, issued on August 26, 1952, or of the general type disclosed by Jimerson U.S. Patent No. 2,814,277, issued November 26, 1957. The device of the present invention is believed to be a significant improvement over the devices shown in the aforesaid Disser and Jimerson patents as well as the Torreson U.S. Patent No. 2,250,736, issued July 29, 1941.

Generally stated, the embodiment of the attachment, 25 illustrated in Figs. 1-5, utilizes a tapered torsional member 4 which may be of solid or longitudinally laminated construction, the effective length and sectional modulus of which are varied by a sliding member 5.

More particularly, referring to the drawings, the 30 numeral 1 indicates a housing which may be cylindrical or substantially cylindrical in form. At one end of this housing is fixedly secured a plug or driven head member 2. The driven head member 2 is provided with a non-circular socket 9 upon which force is applied for the 35 purpose of tightening up a bolt, nut or the like as will appear in the following description. The device can be attached to an electric or pneumatic rotary impact wrench. A transverse circular plate 3 is rigidly secured in place immediately adjacent member 2. Member 3 is

40 provided with a central circular opening which receives a short cylindrical extension at one end of a longitudinally disposed tapered torsion member 4. The other end of torsion member 4 is supported in a rotatable disc 7 which is retained in an annular internal groove at one 45 end of the housing 1. Disc 7 is provided with a square or rectangular opening therethrough which fits the rectangular cross section of extension 8 of the tapered torsion member 4.

Two sets of opposed circular apertures 11 are provided 50 through the cylindrical surface of housing 1, each set of apertures in staggered relation to the other as will be clear from Figure 1.

A movable plug element 5 is slidably received in the 55 interior of the housing 1 and is provided with a slot 6 therethrough to accommodate the maximum tapered dimension of torsion member 4 and be positioned at various axial positions longitudinally of the housing. The element 5 carries in its peripheral surface two diametrically opposed radial tapped holes or bores into which 60 may be threaded machine screws 10 which in cooperation with the holes 11 in the housing provide a convenient means for positively holding element 5 in one of its possible positions along the interior bore of housing 1.

The extension 8 of torsion member 4 is of rectangular 65 transverse cross-section and is frictionally engaged by a bolt or nut engaging socket so that the driving forces may be transmitted thereto to tighten or otherwise act upon a bolt or nut. The operational relationship of rotary impact wrench, torque limiting device, bolt engaging 70 socket and bolt is believed to be clear from the showing of Fig. 10.

In operation, with the element 5 secured in one of its

axial positions by screws 10, the socket 9 is engaged by the driving member of a power impact wrench while extension element 8 is drivingly connected to a bolt or nut through a socket member, as S.

Upon operation of the wrench, the applied torque will initially be transmitted through element 9, housing 1, screws 10, element 5, torsion member 4, extension 8, and socket S to the fastener. The fastener will be rapidly tightened to the point under conventional power impact wrench operation at which continuous drive ceases and intermittent drive impulses or impacts commence due to the inherent operation of the impact wrenches. Up to this point the torsion member has transmitted the torque from the wrench undiminished to the socket and fastener. However, as the fastener is set up more tightly, its resistance to the transmitted torque becomes increasingly greater. With this increase in the fastener's resistance to turning, the torsion member begins to absorb, within itself, an increasing part of the turning energy which is now being delivered in impulses. This part of the absorbed energy is absorbed by torsional flexing of the torsion member. This energy which is resiliently or elastically absorbed by torsional flexing, of course, is returned by the torsional member through the tool anvil to the rebounding hammer. For a given selected position of element 5 and hence selected torsion quality for the torsion member, a point in the fastener tightening process will be reached at which the fastener is so tightened that its resistance to further turning becomes very great. Hence, since the energy of the repeated impacts or torque impulses received from the power wrench remain substantially constant, when the above point is reached, most of the energy of the torque impulse received from the wrench hammer is absorbed by torsional flexing of the torsion member and in effect a negligible fraction thereof is transmitted through the torsion member to the fasteners. At this point the torque applied to the fastener has been effectively limited for a given axial position of element 5 along the torsion member 4. It is also important to note that at this point of maximum resistance of the fastener and maximum energy absorption by flexing of the torsional member, that the rotational and axial rebound of the hammer element of the conventional power wrench also reaches a maximum amplitude.

In conventional power impact wrenches of the type which do not have a shut-off mechanism responsive to a predetermined hammer element rebound condition, the tool will continue to operate after the above discussed point of maximum energy absorption by the torsion member but no appreciable amount of energy will be transferred to the fastener. Under these conditions the rotary impact wrench is operated for a period of time corresponding to appreciable continued movement of the fastener and then terminated. This will result in the imposition of some general limit on the torque applied to tightened fasteners.

In conventional rotary impact wrenches of the type which have a shut-off mechanism responsive to a predetermined hammer rebound condition, the tool will be shut off when the predetermined rebound condition obtains, which will be directly controlled by the torsional characteristics selected for the torsion member. With this type tool termination of tool operation is automatic. It will be understood that by providing a tapered torsion member with variable effective length as shown in Figures 1-5 a very wide range of torsion characteristics and hence torque limits can be covered with one small size torsion member which in turn controls the size of the torque limiting device. A reversal of direction of drive requires no adjustment or changes whatsoever and the change in torque setting desired is easily and simply accomplished with a screwdriver. The holes in the housing can easily be provided with indicia showing the torque limit for each setting of the element 5. A modified ver-

sion of an improved torque limiting device embodying features of the present invention is disclosed in Figures 6-9. Outstanding features and advantages of this version are its compact size and infinitely variable selection of the desired torque limit. It also is capable of reversible operation without adjustment or modification.

Reference numeral 21 indicates an elongated hollow housing preferably of polygonal transverse cross section. Secured in one end of housing 21 is a driving head member 22 the transverse cross section of which is circular and fits into the interior of housing 21. Member 22 abuts inturned flange elements at one end of the housing 21 and is provided with a plurality of circumferentially spaced axially extending bores into which are fitted a plurality of elongated pins 24. The elongated pins are slidably supported in corresponding circumferentially spaced axially extending passageways through a sliding block 25 which has a transverse cross section matching that of the interior of housing 21. The other ends of pins 24 abut a disc member 26 which is backed up by an annular end closure member 28 also slidably received and fitted into the interiors of the housing 21. Member 28 is the driven member and is locked in place by a radial screw 39 extending through the housing into a threaded bore in member 28. A threaded shaft 23 is journaled at one end in a bore in the inner transverse face of member 22 and at the other end in a bore through disc 26, passing through in threaded engagement with block 25. A spring detent acts between disc 26 and member 28 to eliminate play between the parts. The exposed end of threaded shaft 23 is slotted to receive and be rotated by a screwdriver or like tool. It will be observed that such rotation of shaft 23 axially positions the block 25 in the housing and varies the effective length of pins 24 as torque transmitting elements.

In operation the modified device of Figures 6-9 functions essentially the same as that disclosed in Figures 1-5, the plurality of pins 24 acting as a series of torsion members in limiting the transmitted torque. In this modification the driven member 28 transmits torque to the housing 21 which through its non-rotating fit with sliding block 25 transmits torque thereto. The driving head member 22 is, as noted, rotatable with respect to the housing 21 and receives torque therefrom through the variable effective length of the pins 24 extending between the block 25 and the driving head member 22. Suitable indicia means can be provided to show the torque settings for each position of block 25. One way of doing this is the provision of a slot longitudinally arranged in the housing 21 with the desired scale marked along one side thereof to be read against an index mark on the peripheral surface of block 25.

The version of the device shown in Figures 11-14 is of similar construction and operates in a similar fashion to the earlier disclosed versions and utilizes a torsion member of laminated construction. It has been determined that there are advantages in making the torsion element such as 4 of longitudinally laminated multi-leaf construction. This results in a greater deflection for a given torsional stress and will provide a torsion element of increased life under severe usage.

From a review of Figs. 12-14 in conjunction with the foregoing disclosure of the device as illustrated in Figs. 1-10, it will be apparent to those skilled in the art that the housing 51 is of the same general configuration and function as housings 1 and 21 of the other figures. The torsion element 52 of Figs. 12-14 performs the same general function as the torsion element 4 and plurality of torsion elements 24 in the devices of the other figures. It will also be clear that slidably adjustable element 55 of Figs. 12-14 operates in a manner similar to element 5 of Figs. 1-5 and similar to element 25 of Figs. 6-9. Element 59 is a circular collar unit frictionally slidably fitted on the exterior of torsion element 52. Element 58 is an annular plug element fitted into the

rear of the housing and secured in place by machine screw 56. Threaded shaft 53 is rotatably secured in plug element 58 and is in threaded engagement with element 55 to move element 55 axially in the housing to vary the effective length of the torque-transmitting portion of element 52. An index mark on element 55 can be read against the scale 60 in the housing to set the variable effective length of element 52 accurately.

In this case the driven member 58 through its connection to the housing 51 transmits torque thereto and the housing 51 through its sliding but non-rotating connection with the adjustable element 55 transmits torque thereto. The adjustable element 55 is non-rotatably engaged with the torsion element 52 which by virtue of the slidable adjustment permitted element 55 constitutes a torsion bar of variable effective length to transmit torque to the driving socket wrench or other element affixed to the exposed end of the element 52. The member 59 being rotatable in the end of housing 51 does not enter into the torque transmitting chain but does serve to bind the assembly together.

Having specifically described two modifications of improved devices embodying our invention we desire to determine the limits of the invention according to the scope of the following claims.

We claim:

1. A rotary impact device comprising in combination, a housing, driving means on end of the housing, a driven element connected to the other end of said housing, a torsion member drivingly connected to said driving means and the driven element and having a continuously varied cross section, and means engaging said torsion member cooperating therewith to selectively vary the effective length and selectively utilize one cross sectional area of said torsion element and establish a desired limiting impact torque which can be transmitted from said driving means to said driven element corresponding to the cross section and effective length of the torsion member selected.

2. A rotary impact torque limiting device comprising in combination a housing, driving means mounted on one end of the housing, a driven element mounted at the other end of said housing, a plurality of torsion members in continuous driving engagement between said driving means and said driven element and manually operative means for selectively varying the effective length of said torsion members to determine the limiting torque which can be transmitted from said driving means to said driven element.

3. A reversible rotary impact torque limiting unit 50 comprising in combination an elongated hollow hous-

ing, a driving member mounted at one end of said housing, a driven element positioned at the other end of said housing, a laminated torsion member continuously connected between said driving member and said driven element, said torsion member being of selectively variable unstressed spring characteristics to selectively determine and limit the maximum impact torque transmitted from said driving member to said driven member.

4. In a rotary impact tool of the class described, a 10 driving member and a driven member infinitely variable torsion spring means connected between said members for transmitting movement of the driving member to the driven member and means for selectively varying the effective elastic characteristics of said spring means so that 15 it serves a substantially rigid connection between said members so long as the force with which the driven member is moved below the corresponding value corresponding to the elastic characteristic selected and as an elastic connection whenever such force exceeds said corresponding value.

5. An impact torque limiting attachment for a rotary impact tool comprising an elongated hollow housing, a driving connector element rigidly secured at one end of said housing and adopted to be drivingly engaged with 25 a rotary impact tool, a torsion means continuously drivingly engaged with said driving connector element, adjustable means cooperating with said torsion means to vary the effective length thereof to determine the maximum torque to be transmitted through the attachment, and a driven element in continuous driving engagement 30 with said torsion means.

6. An impact torque limiting device for combination with a rotary impact wrench comprising an elongated hollow casing having a driving element rigidly secured thereto at one end, a tapered elongated resilient torsion member longitudinally supported in said casing for rotary motion therein, a driven element drivingly connected with one end of said torsion member, and a longitudinally movable block mounted in said casing to rigidly connect said casing to said torsion member at selected points along its length to determine selectively the maximum torque transmitted from said driving element and casing to said driven element.
